UNITED STATES PATENT OFFICE

1,928,486

SEWING MACHINE FRAME

Horace F. Gruman, St. Louis, Mo., assignor to
Lewis Invisible Stitch Machine Company, St.
Louis, Mo., a corporation of Maine

Original application Serial No. 512,666, January
31, 1931. Divided and this application Septem-
ber 19, 1931

Serial No. 563,840

3 Claims. (Cl. 112—258)

This invention relates to new and useful im-
provements in sewing machine frames of the
feed-off-the-arm type, and constitutes a division
of my co-pending application Serial No. 512,661,
5 filed January 31, 1931 for improvements in sew-
ing machines.

Among the several objects of my invention are
to provide a sewing machine frame of the feed-
off-the-arm type wherein the standard is cen-
trally located relative to the overhanging arm
10 and the front horizontal section of the work
supporting arm; to provide such a frame with a
standard having a forwardly and upwardly ex-
tending portion to which one end of the hori-
zontal section of the work supporting arm is detach-
ably connected, whereby the operating parts in
the entire work arm may be readily assembled
15 and then attached to the standard, and to provide
such a frame with a detachable head carrying
the entire rear stitch forming mechanism.

With these and other objects in view which will
more fully appear, the nature of the invention
will be more clearly understood by following the
25 description, the appended claims, and the sev-
eral views illustrated in the accompanying draw-
ings.

In the drawings:—

Figure 1 is a perspective view of a sewing ma-
chine frame embodying my invention.

Figure 2 is a transverse vertical section there-
of, the driving connections in the standard and
the mechanism in the work arm being omitted.

Figure 3 is a perspective view of the standard.

Figure 4 is a perspective view showing particu-
larly the attaching end of the work arm.

Figure 5 is a detail vertical sectional view show-
ing the means for detachably connecting the
stitching head to the overhanging arm of the
frame.

Figure 6 is a cross sectional view taken on
the line 6—6 of Figure 5, and

Figure 7 is an elevation of the right hand side
of the frame.

Like reference numerals designate correspond-
ing parts throughout the several figures of the
drawings.

As shown in the drawings, the frame C em-
bodies a hollow standard 5 which includes an
upwardly and rearwardly extending hollow por-
tion 6 and an upwardly and forwardly extending
hollow portion 7, an overhanging arm 8 which
extends laterally from the upper end of the rear-
wardly extending portion 6 of the standard, a
stitching head 9 detachably connected to the
outer end of the overhanging arm 8, and a tubu-

lar work arm 10 which is detachably connected
at one end to and entirely supported by the up-
per end of the forwardly extending portion 7
of the standard. The work arm 10 includes a
front horizontal arm 11 which is disposed in 60
parallelism with but in a plane lower than the
overhanging arm and is connected at one end to
the standard as above stated, a vertical or drop
arm 12 which depends from the other end of the
front arm 11, and a horizontal work supporting 65
arm 13 which is spaced from the standard and
extends rearwardly from the lower end of the
vertical or drop arm 12 and has its free end ter-
minating under the stitching head 9. It will thus
be seen that the standard is located centrally 70
relative to the overhanging arm 8 and the front
horizontal arm 11, and therefore the weight of
said overhanging arm and said work arm is fairly
well distributed, whereby the vibrations of the
machine when the latter is operating at high 75
speed, will be reduced to a minimum.

The upper part of the forwardly extending por-
tion 7 of the standard is provided with a right
angle cut-out 14 forming an angular seat com-
prising a horizontal surface 15 and a vertical sur-
face 16. The vertical surface 16 is disposed in a 80
plane parallel with the longitudinal axis of the
overhanging arm 8, and the horizontal surface 15
extends forwardly from the bottom of the ver-
tical surface. A perforated centering lug 17 pro-
jects downwardly from the top of the forwardly
extending portion 7 and the front face of this 85
lug lies in the plane containing the vertical face
16. Fastening lugs 18 project inwardly from op-
posite sides of the forwardly extending portion 7
and have their upper faces in the plane of the 90
horizontal surface 15. The attaching end of the
work arm 10 is provided with an arm 19 which
is integral with and extends rearwardly from the
front horizontal arm 11 and is shaped to form a 95
right angle including a rear vertical surface 20
and an under horizontal surface 21 so as to fit
the seat 14, with the vertical surface 20 abut-
ting the vertical surface 16 and the horizontal 100
surface 21 abutting or resting upon the horizon-
tal surface 15. A perforated centering lug 22
projects downwardly from the rear end of the
attaching arm 19 and the rear face of this lug
lies in the plane of the vertical surface 20. The 105
lugs 17 and 22 and the perforations thereof are
disposed in registration, and a dowel pin 23 is
positioned within the perforations to insure
proper cooperation between the working instru-
mentalities in the work arm section 12 and the
work instrumentalities mounted on the detach- 110

able head 9. Fastening lugs 24 project inwardly from opposite sides of the attaching arm 19 and have their lower faces in the plane of the horizontal surface 21. The fastening lugs 18 and 24 are disposed in registration and are held against movement by fastening screws 25. Thus it will be seen that the work arm 10 is detachably connected to the standard, and that said detachable connection forms the sole supporting means for the work arm.

The outer end of the overhanging arm 8 is closed by a vertical wall 26, and the inner end of the stitching head 9 is closed by a vertical wall 27 which abuts the wall 26. A main rotary shaft 28 is journaled in the overhanging arm 8 and the driven end thereof projects through a bearing 29 into the head 9, the bearing 29 being rigidly connected to the wall 27 of the head, as by threaded engagement, and projecting outwardly from said wall into an opening 30 formed in the wall 26 of the overhanging arm. Dowel pins 31, 31 are fixedly connected to the wall 27 of the head on opposite sides of the bearing 29 and extend outwardly into openings 32, 32 formed in the wall 26 of the overhanging arm. Set screws 33, 33 are threaded into openings formed in the wall 26 and the inner ends 34, 34 of said screws are tapered and engage in transverse openings 31^a, 31^a formed in the dowel pins 31, 31, and thereby not only draw the wall 27 of the head 9 tightly against the wall 26 of the overhanging arm but also maintain said head against turning movement about the shaft 28.

It is of course to be understood that the details of structure and arrangements of parts may be variously changed and modified without departing from the spirit and scope of my invention.

I claim:—

1. A sewing machine frame comprising a hollow standard having a forwardly extending portion, an overhanging arm extending laterally from the upper end of the standard, the upper part of the forward end of the forwardly extend-

ing portion of the standard being formed with an angular seat including a substantially vertical surface extending in a plane substantially parallel to the plane of the overhanging arm and a substantially horizontal surface extending forwardly from the bottom of the vertical surface, and a tubular work arm having its free end disposed under the overhanging arm and having its other end shaped to fit said seat and detachably connected thereto.

2. A sewing machine frame comprising a hollow standard having a forwardly extending portion, an overhanging arm extending laterally from the upper end of the standard, the upper part of the forward end of the forwardly extending portion of the standard being formed with an angular seat including a substantially vertical surface extending in a plane substantially parallel to the plane of the overhanging arm and a substantially horizontal surface extending forwardly from the bottom of the vertical surface, and a tubular work arm having its free end disposed under the overhanging arm and having a rearwardly extending attaching arm having an under horizontal surface seated on the horizontal surface of the angular seat and having a rear vertical surface abutting the vertical surface of the seat, and means detachably connecting the attaching arm to the standard.

3. A sewing machine comprising a standard having a work support and a tubular overhanging arm element having a closing wall at its outer end, a stitching head element having a closing wall at its inner end, and means for detachably connecting the arm and head comprising a dowel pin fixed to one wall and extending into a corresponding opening in the other wall and formed with a transverse opening, and a set screw having threaded engagement with the element to which the dowel pin is fixed and having a tapered end seated in the transverse opening of the dowel pin to draw said elements together.

HORACE F. GRUMAN.
